WILTON TELFER, OF WINNIPEG, MANITOBA, CANADA.

ATTACHMENT TO WASHBASIN DRAIN-PIPES.

1,086,482.

Specification of Letters Patent. Patented Feb. 10, 1914.

Application filed September 3, 1912. Serial No. 718,379.

To all whom it may concern:

Be it known that I, WILTON TELFER, of the city of Winnipeg, in the Province of Manitoba, Canada, have invented certain new and useful Improvements in Attachments to Washbasin Drain-Pipes, of which the following is the specification.

The invention relates to a device attachable to the ordinary drain pipe of a wash basin and the object of the invention is to provide an inexpensive and efficient device which can be readily attached to the drain pipe and will operate to prevent the pipe from freezing up.

15 The device is particularly designed for use on railroad cars where considerable difficulty is experienced in colder countries owing to the pipes freezing up due to the taps leaking. Drops of water trickle down the 20 drain pipe and freeze at the lower end where the pipe opens to the exterior of the car. An icicle forms and accordingly enlarges until the pipe is completely closed. With 25 my device attached the probability of this happening is reduced to a minimum.

It consists essentially in a small reservoir attached to and opening to the drain pipe and carrying a flushing valve, the reservoir being arranged to collect water and free it 30 in quantities, the freed water being passed around the drain pipe, the parts being arranged and constructed as hereinafter more particularly described.

Figure 1 represents a vertical sectional view through the device showing it applied to a wash basin. Fig. 2 represents an enlarged detailed horizontal sectional view through the reservoir, the section being taken in the plane denoted by the line 40 Y—Y' Fig. 1. Fig. 3 is an enlarged detailed vertical sectional view through the seat.

In the drawing like characters of reference indicate corresponding parts in each figure.

1 represents a wash basin fitted with the usual taps 2 and 3 and plug 4 which closes the opening in the basin.

5 represents a casting providing a reservoir 50 7 having a cross plate or partition therein fitted with a valve opening or passageway 8 the plate dividing the reservoir into two compartments "a" and "b". The casting is formed also with a single intake 55 pipe 9 leading to the reservoir and two outlet pipes 10 and 11 leading therefrom, the

one being contained within the other. The pipe 10 is in reality an extension of the pipe 9 and opens to that portion of the reservoir above the dividing plate while the pipe 11 60 opens to the reservoir beneath the dividing plate. The pipe 9 screws into the usual boss 12 formed on the water basin.

13 is a drain pipe connected directly with the pipe 10 which pipe passes beneath the car 65 floor 14 and terminates about the same point as the present drain pipe. 15 is a second pipe receiving the pipe 13 and coupled up with the pipe 11. This pipe passes also through the car floor and terminates slightly 70 above the lower end of the pipe 13.

The bottom of the reservoir 6 is closed by a screw plug 16 which carries a stuffing box 17, the stuffing box forming the bearing for the stem 18 of the valve 19. The valve 75 is fitted with a rubber or other such like washer 20 which engages with a further rubber or such like washer 21 carried by the dividing plate 7.

22 is a lever pivotally secured at 23 to the 80 side of the casting and having the lower end thereof slotted at 24 and receiving a pin 25 carried by the lower end of the valve stem. A weight 26 is adjustably secured to the upper end of the lever by a set screw 27. It is 85 to be noticed that the lever is constructed so that very little downward motion on the part of the valve causes the weight to assume practically an upright position. The reason for this will be more apparent later. 90

In order to understand the device more thoroughly I will now describe its operation assuming that the pipe 13 has become closed up through ice 28 forming on the lower end thereof.

When a party has finished using the wash basin he releases the water 29 therein by withdrawing the plug 4 in the usual way. This water flows down the pipe 9 to the pipe 13 where it backs up owing to the ice and 100 overflows into the top of the reservoir. The valve is normally held shut by the weight. However as soon as the weight of the water overflowing into the reservoir becomes great enough to force the valve down the water in 105 the reservoir will be free to escape to the pipe 10 and then directly to the pipe 15. This water which is more or less warm will operate to thaw out the pipe 13. It will be noticed that as soon as the valve is forced 110 down the action of the weight becomes accordingly lessened through its being passed

more to the upright position, that is, to a point more or less vertically above the pivot pin 23. It is intended that the valve and weight shall be adjusted so that the valve will have no tendency to close until all the water is passed out of the reservoir, in other words the initial tendency of the valve of itself to remain unseated with no water in the reservoir will just be overcome by the 10 tendency of the weight to swing from a point almost directly above the pivot pin 23 to its lower position. This feature of the attachment assures that the water will be expelled from the reservoir in sufficient quantities 15 through the pipes 11 and 15 to have a thawing out effect on the pipe 28. In case the pipe is frozen up by the taps leaking and no one uses the basin the water leaking from the taps will trickle down the pipes 9 and 13 and 20 gradually back up the pipes and overflow into the top portion of the reservoir. This will continue until the reservoir is filled to a sufficient height to set off the valve in the same manner as that previously described.

25 What I claim as my invention is:—

1. The combination with a wash basin, and a drain pipe passing from the same, of a divided reservoir having two compartments therein, one of said compartments opening 30 to the drain pipe, a pipe receiving the drain pipe and opening to the other of the compartments and means for controlling the flow of a liquid from one compartment to another, as and for the purpose specified.

25 2. The combination with a wash basin and a drain pipe passing from the same, of a divided reservoir having two compartments therein, one of said compartments opening to the drain pipe, a pipe receiving the drain 40 pipe and opening to the other of the compartments and a valve controlling the flow of a liquid from one compartment to the other, as and for the purpose specified.

3. The combination with a wash basin and 45 a drain pipe passing from the same, of a reservoir having two compartments therein connected through a suitable passage way, one of said compartments opening to the drain pipe, a pipe receiving the drain pipe 50 and opening to the other of the compartments and means controlling the flow of a liquid through the passageway, as and for the purpose specified.

4. The combination with a wash basin, and 55 a drain pipe passing from the same, of a reservoir having two compartments therein connected through a suitable passage-way, one of said compartments opening to the drain pipe, a pipe receiving the drain pipe 60 and opening to the other of the compartments, and a valve normally closing the passage, as and for the purpose specified.

5. The combination with a wash basin and 65 a drain pipe passing from the same, of a reservoir having two compartments therein

connected through a suitable passage-way, one of said compartments opening to the drain pipe, a pipe receiving the drain pipe and opening to the other of the compartments, a valve and means for normally seating the valve to close the passage-way, as and for the purpose specified. 70

6. The combination with a wash basin, and a drain pipe passing from the same, of a reservoir having a horizontally disposed partition therein forming a top and bottom compartment, there being a valve opening in the partition connecting the compartments the top compartment opening further to the drain pipe, a pipe receiving the drain pipe and opening to the bottom compartment and a valve beneath the partition arranged to seat on the under side thereof and close the valve opening, as and for the purpose specified. 75

80 7. The combination with a wash basin, and a drain pipe passing from the same, of a reservoir having a horizontally disposed partition therein forming a top and bottom compartment, there being a valve opening in the partition connecting the compartments, the top compartment opening further to the drain pipe, a pipe receiving the drain pipe and opening to the bottom compartment, a valve located beneath the partition and arranged to seat on the under side thereof and close the valve opening and means holding the valve normally seated, as and for the purpose specified. 85

90 8. The combination with a wash basin, and a drain pipe passing from the same, of a reservoir having a horizontally disposed partition therein forming a top and bottom compartment, there being a valve opening in the partition connecting the compartments, the top compartment opening further to the drain pipe, a pipe receiving the drain pipe and opening to the bottom compartment, a valve located beneath the partition and arranged to seat on the under side thereof and close the valve opening, a pivoted lever connected to the valve and an adjustable weight carried by the lever, as and for the purpose specified. 95

100 9. The combination with a wash basin, and a drain pipe passing from the same, of a reservoir having a horizontally disposed partition therein forming a top and bottom compartment, there being a valve opening in the partition connecting the compartments, the top compartment opening further to the drain pipe, a pipe receiving the drain pipe and opening to the bottom compartment, a valve located beneath the partition and designed to seat on the under side thereof to close the opening, a stem extending from the valve and slidably mounted in the bottom of the reservoir, a lever pivotally secured to the reservoir and connected with the valve stem, and a weight adjustably se- 110 115 120 125 130

cured to the lever, as and for the purpose specified.

10. The combination with a wash basin, and a drain pipe passing from the same, of a reservoir having a horizontally disposed partition therein forming a top and bottom compartment, there being a valve opening in the partition connecting the compartments, the top compartment opening further to the drain pipe, a pipe receiving the drain pipe and opening to the bottom compartment, a valve located beneath the partition and designed to seat on the under side thereof to close the opening, a stem extending from the valve and slidably mounted in the bottom of the reservoir, a stuffing box carried by the bottom of the reservoir and receiving the valve stem slidably, the said stuffing box passing well into the bottom compartment, a lever pivotally secured to the reservoir and connected to the valve stem and an adjustable weight secured to the lever, as and for the purpose specified.

11. In a device of the class described a reservoir having an internal partition therein provided with a valve opening and providing a top and bottom compartment and being provided further with a pipe opening to the top compartment, a pipe passing from

the top compartment and a pipe containing the latter pipe and opening to the bottom compartment, as and for the purpose specified.

12. The combination with a drain pipe adapted to receive drained water, of a reservoir having a horizontally disposed cross partition therein providing a top and bottom compartment the partition being supplied with a valve opening and the top compartment being open to the drain pipe to admit water to the compartment, a pipe communicating with the bottom compartment and containing a portion of the drain pipe and a balanced valve normally closing the valve opening and arranged to automatically open and flush out the top compartment and admit the water to the pipe communicating with the bottom compartment, said valve being balanced to remain closed until a considerable quantity of water is stored in the top compartment, as and for the purpose specified.

Signed at Winnipeg, this 15th day of April, 1912.

WILTON TELFER.
